United States Patent Office

Des. 215,889
Patented Nov. 4, 1969

215,889

MICROSCOPE

Taiichi Suzuki, Tokyo, Japan, assignor to Swift Instruments, Inc., Boston, Mass., a corporation of Massachusetts

Filed Oct. 25, 1968, Ser. No. 14,183

Term of patent 14 years

Int. Cl. D16—08

U.S. Cl. D57—1

FIG. 1

FIG. 2

FIG. 1 is a perspective view of a microscope, showing my new design;

FIG. 2 is a top plan view thereof;

FIG. 3 is a perspective view as seen from the opposite side of FIG. 1;

FIG. 4 is a sectional view taken along the line IV—IV in FIG. 3.

I claim:

The ornamental design for a microscope, as shown and described.
